UNITED STATES PATENT OFFICE.

ADELBERT B. CASE, OF SPRINGFIELD, MASSACHUSETTS.

DESIGN FOR A FRAME FOR CLOTHES-WRINGERS.

SPECIFICATION forming part of Design No. 24,346, dated May 28, 1895.

Application filed April 5, 1895. Serial No. 544,679. Term of patent 14 years.

To all whom it may concern:

Be it known that I, ADELBERT B. CASE, a citizen of the United States, residing at Springfield, in the county of Hampden and State of Massachusetts, have invented a new and original Design for a Clothes-Wringer Frame, of which the following is a specification, reference being had to the accompanying drawing, showing the same.

10 The leading feature of my design consists in a clothes-wringer frame the end standards and top-brace of which present to the eye a rounded or curved surface.

Referring to the drawing, the letters *aa* designate the two end standards of the wringer-frame, each of which standards has its upper portion composed of two members, concavo-convex in cross-section, joined by a U-bend at their upper ends, and their convex surfaces 20 being outermost.

The letter *b* designates the top-brace, which is round in cross-section, and has an annular beaded formation *b'* adjacent to the inner edge of the standards *aa* and a rounded end *b²* at the outer edge of said standards. Said standards and top-brace, by presenting to the eye a rounded or curved surface at every point, give to the wringer-frame an exceedingly graceful and pleasing appearance.

Having thus fully described my design, 30 what I claim, and desire to secure by Letters Patent, is—

The design for a clothes-wringer frame substantially as herein shown and described.

ADELBERT B. CASE.
